UNITED STATES PATENT OFFICE.

CHARLES COLIN GLENN HOYLE AND GERALD LAY HART, OF CALCUTTA, INDIA,
ASSIGNORS TO ALEXANDER FRANK NEWELL, OF CALCUTTA, INDIA.

CLOSURE FOR RECEPTACLES.

1,276,768.

Specification of Letters Patent. Patented Aug. 27, 1918.

Application filed August 9, 1917. Serial No. 185,349.

To all whom it may concern:

Be it known that we, CHARLES COLIN GLENN HOYLE and GERALD LAY HART, both being subjects of the King of Great Britain and Ireland and Emperor of India, and having their post-office addresses at No. 4 and No. 5, respectively, Mint Buildings, Strand Road, Calcutta, British India, have invented certain new and useful Improvements in or Relating to Closures for Receptacles such as Cannisters, Drums, Casks, and the like, of which the following is a specification.

This invention relates to closures for receptacles such as cannisters, drums, casks, and the like, and is an improvement on that type of closure the opening of which necessitates the destruction or defacement of a lead or other seal; its object being to prevent the unauthorized opening of such receptacles without detection.

In the accompanying sheet of drawings: Figure 1 shows in sectional elevation a portion of a receptacle fitted with a closure constructed according to this invention. Figs. 2, 3 and 4 are sectional elevations of the component parts of the said closure, while Fig. 5 is an elevational view of the screw stopper and the key used to extract it from the loose cap which covers it and secures in place a lead or other seal.

Referring to the said drawings, in which similar reference letters indicate similar parts throughout the several views, *a* designates a portion of a receptacle having an externally screw-threaded nozzle *b* of the ordinary kind. A screw stopper *c* is screwed firmly to the nozzle *b* by means of a screw-driver or similar tool, the edge of which is inserted in a short groove *e* provided for the purpose in its upper surface.

At diametrically opposite points on the external circumference of the stopper *c* are vertically arranged spring leaves *d* suitably affixed to *c* at their upper ends, while their lower and free ends stand slightly away from its circumference.

The spring leaves *d* serve to secure to the stopper *c* a loose cap *g* having a shoulder *h* around the lower edge of its internal circumference, above and with which the said spring leaves engage when the cap *g* is pressed down over the stopper *c*.

Prior to the cap *g* being secured over the stopper *c*, a disk *f* of lead or other suitable

material is placed on the stopper, and is held in that position when the cap *g* is applied to the stopper *c*.

The receptacle *a* having been closed by the closure assembled as above described and as illustrated in Fig. 1, it will be readily seen that, as the cap *g* entirely covers and rotates freely upon the stopper *c*, the latter can be unscrewed from the nozzle *b* of the receptacle *a* only by piercing and destroying the disk *f* and, through the orifice *i* in the cap *g*, inserting the edge of a screw-driver or similar tool into the groove *e* in the top of the stopper *c*.

The stopper *c* having been thus removed, and before the damaged disk *f* can be replaced, it is necessary to extract the stopper from the loose cap *g*. To enable this to be done, a special key or extractor shown in Fig. 5 is provided. The said key consists of a short cylinder *j*, of thin sheet steel, attached to a suitable handle such as *k*. The cylinder *j* is of a diameter and thickness to adapt it to enter the annular space between the internal periphery of the shoulder *h* of the cap *g*, and the external periphery of the stopper *c*.

At diametrically opposite points in the cylinder *j*, and so as to register with the spring leaves *d* on the stopper *c*, bayonet slots *m* are provided into which the spring leaves *d* enter when the cylinder is inserted in the cap *g*.

The cylinder *j* having been thus inserted, it is rotated axially in a contra clock-wise direction, so that the lips *n* of the bayonet slots *m* pass over the upper and non-projecting ends of the spring leaves *d*. The cylinder *j* being now forcibly withdrawn from the cap *g*, the lips *n* compress the lower and projecting ends of the spring leaves *d* into the portions *o* of the bayonet slots *m* and thus release them from engagement with the internal shoulder *h* of the cap *g*.

Having now fully described and ascertained our said invention and the manner in which it is to be performed, we declare that what we claim is:

1. A closure for receptacles of the character described, comprising in combination, a stopper adapted to be secured to the receptacle, springs externally attached to said stopper, a cap covering said stopper, an internal shoulder on said cap adapted to

- engage with said leaf springs and a lead disk arranged upon said stopper and held in position by said cap, said leaf springs adapted to be engaged by an opening tool for disengaging said springs and the shoulder of said cap, substantially as described.
2. A closure for receptacles of the character described, comprising in combination, a screw stopper adapted to be secured to the nozzle of the receptacle, a loose cap carrying said stopper, an internal shoulder on said cap, a plurality of spring leaves spaced around the external circumference of said stopper and having their upper ends rigidly affixed thereto, and their lower ends slightly outstanding therefrom, said spring capable of being compressed when said cap is pressed upon said stopper and adapted to spring outward into engagement with said internal shoulder, substantially as described.
3. A closure for receptacles of the charac-

ter described, comprising in combination, a screw stopper having a groove in its upper face, adapted to be secured to the nozzle 25 of the receptacle, leaf springs externally attached to said stopper, a loose cap having an orifice covering said stopper, an internal shoulder on said cap adapted to be engaged by said springs, a disk on said stopper held 30 in position thereon by said cap and subject to destruction by a tool introduced through the orifice in said cap into the groove of said stopper for extracting the same, substantially as described. 35

In testimony whereof we have signed this specification in the presence of two witnesses.

CHARLES COLIN GLENN HOYLE.
GERALD LAY HART.
